UNITED STATES PATENT OFFICE.

PAUL G. SHOURDS, OF CHICAGO, ILLINOIS, ASSIGNOR TO AMERICAN BLUE PRINT PAPER COMPANY, OF CHICAGO, ILLINOIS, A CORPORATION OF ILLINOIS.

MACHINE FOR MECHANICAL REPRODUCTION OF INK-DRAWINGS.

1,182,046.

Specification of Letters Patent.

Patented May 9, 1916.

Application filed September 2, 1915. Serial No. 48,612.

To all whom it may concern:

Be it known that I, PAUL G. SHOURDS, a citizen of the United States of America, and a resident of Chicago, county of Cook, and State of Illinois, have invented certain new and useful Improvements in Machines for Mechanical Reproduction of Ink-Drawings, of which the following is a specification.

The main objects of this invention are to provide an improved form of machine for mechanically reproducing ink drawings, tracings, etc.; to provide an improved arrangement of a film-carrying member adapted for use in such a machine; to provide improved means for coating said member with an impression film; and to provide an improved arrangement of pressure-creating means coacting with said film-carrying member to facilitate and insure the accurate reproduction of ink drawings, tracings, etc.

An illustrative embodiment of this invention is shown in the accompanying drawings, in which—

Figure 1 is a side elevation of the improved machine. Fig. 2 is an end view taken from the right of Fig. 1, the pressure roller being shown in its elevated position. Fig. 3 is a plan of the right hand end of the machine. Fig. 4 is an enlarged detail partly sectional of the truck which assists in the support of the carriage.

In the construction shown in the drawings, the machine comprises a horizontally disposed table 1 supported on standards or legs 2 and carrying rollers 3, 4, 5 and 6 arranged to move and guide a film-carrying member or belt 7 on the said table 1. A carriage 8 is reciprocatingly mounted on the table 1 so as to move a roller 9 back and forth over the film-carrying member or belt 7.

The film-carrying member or belt 7 may be of any suitable flexible material, preferably non-absorbent. Linoleum or oilcloth has been found to be a very satisfactory material for this purpose. The rollers 3 and 4 are located at opposite ends of the table 1 so that their peripheries are substantially in alinement with the top of the table, whereby the belt 7 is properly guided in its movements onto and off from the table.

The impression film is formed on the face of the belt 7 by passing the belt through a

suitable bath. This has been conveniently arranged for in the construction herein illustrated, by mounting the roller 5 directly below the roller 4 and placing the roller or idler 6 above and inward from the roller 5, which guides the belt 7 so as to permit a trough 10 to be suspended below the roller 5 in position to embrace the lower part thereof. The trough 10 is filled with a special liquid composition which adheres to the belt as it is passed therethrough, and produces a gelatinous film on the face of the belt. This film is adapted to receive an impression, from a suitable chemically prepared negative, which is capable of being transferred to drawing materials, such as paper, tracing cloth, etc.

The trough 10 is arranged to be moved into and out of position for immersing the belt 7. This may be conveniently accomplished by means of ropes or other flexible members 11 secured at the ends of the trough and passing around guide rollers 12 to a drum 13 mounted on the legs 2. The drum 13 is provided with a handle 14, by which it is operated, and a ratchet 15 and pawl 16 for retaining the trough 10 in any desired position.

The carriage 8 is provided with flanged rollers 17 which engage tracks 18 formed along the edges of the table 1. A motor 19 is mounted on the carriage 8, and by means of a worm 20 and gear 21 is connected to a driving shaft 22. Pinions 23 secured to the ends of the shaft 22 engage and drive gears 24 which mesh with racks 25, formed along the edges of the table 1 outwardly of the tracks 18.

The motor 19 is of the reversible type and is controlled by a suitable three-way switch 26, herein shown to be mounted on the motor itself. The contacts of the switch 26 are arranged so as to allow the motor to remain inoperative, or cause it to drive the carriage 8 either forward or backward as occasion may require.

The roller 9 is rotatably mounted on cam bearings 27 which are eccentrically connected to a shaft 28, journaled in bearings 29 on the carriage 8. Hand levers 30 are integrally secured to the cams 27 by means of which the shaft 28 may be rotated for the purpose of shifting the cam bearings 27,

and causing the roller 9 to be moved into and out of position to coact with the film-carrying member or belt 7. The roller 9 is covered with a jacket of rubber, leather or other similar material. When the arms 30 are shifted to the positions indicated in the figures, the roller 9 contacts with the film on the belt 7, and the rollers 17 are out of engagement with the tracks 18. When the levers 30 are shifted to their opposite positions (180 degrees) the rollers engage their tracks 18 and raise the roller 9 out of contact with the belt 7.

A motor 31 is herein shown to be connected by a belt 32 and worm 33 and gear 34 to drive the roller 5 for the purpose of moving the belt 7 over the table 1. The shaft 35 for the roller 3 is mounted in bearings 36 shiftably mounted on the brackets 37, each of which is provided with an adjusting screw 38 for regulating the tension of the belt 7.

The operation of the device shown is as follows:—When it is desired to make a quantity of ink reproductions of a certain drawing, a suitable chemically treated negative is obtained from said drawing. The motor 31 is then operated so as to move the belt 7 through the liquid in the trough 10 and onto the table 1 until a sufficient portion of the coated belt is on the table to receive the size of the drawing to be reproduced. The negative above referred to is then placed upon the film and the motor 19 operated to move the roller across said negative, whereupon the lines on the negative are reproduced upon the film. After the roller has traversed the entire length of the negative, it is elevated and the carriage 40 returned to its normal position. The negative is then removed from the film and the film has a coating of ink applied thereto by means of a roller, or in any other suitable manner. The sheets of drawing material, such as paper or tracing cloth, upon which the reproductions are desired, are then placed one at a time upon the film of the belt 7, whereupon the roller 9 is lowered and the carriage 8 is moved to cause said roller to traverse the entire length of said material as it bears thereupon. At the end of the travel of the carriage the roller 9 is again elevated and the carriage returned to its normal position. The sheet of drawing material is removed and without reinking the films the operation is repeated until the desired number of reproductions have been obtained. After the desired number of reproductions have been made, the film is removed from the belt by means of a suitable scraper, whereupon the machine is ready to be used for reproducing other sets of drawings in like manner. It will thus be observed that this arrangement of a machine for mechanically reproducing ink

drawings makes it possible to obtain reproductions in quantities in a very short length of time, the accuracy of which is assured by reason of the arrangement of the roller 9 and the carriage 8 on the table 1.

Although but one specific embodiment of this invention has been herein shown and described, it will be understood that numerous details of the construction shown may be altered or omitted without departing from the spirit of this invention as defined by the following claims.

I claim:—

1. A machine of the class described, comprising a frame, a film-carrying member supported on said frame, means on said frame coacting with said member to form an impression film thereon adapted to receive a design, a roller mounted to traverse said member, means for relatively shifting said member and roller into and out of position to coact with said film, and mechanism for causing the relative movement of said member and roller along said member.

2. A machine of the class described, comprising a film-carrying member, a bath arranged to have said member pass therethrough for forming an impression film on said member adapted to receive a design, a roller mounted to traverse said member, means for relatively shifting said member and roller into and out of position to coact with said film, and mechanism for causing the relative movement of said member and roller along said member.

3. A machine of the class described, comprising a film-carrying member, a bath arranged to have said member pass therethrough for forming an impression film on said member adapted to receive a design, a roller mounted to traverse said member, means for relatively shifting said member and roller into and out of position to coact with said film, mechanism for causing the relative movement of said member and roller along said member, and means for shifting said bath into and out of position for coating said member with an impression film.

4. A machine of the class described, comprising a table, rollers mounted on said table, a belt passing around said rollers and across said table, means for coating said belt with an impression film adapted to receive a design, a carriage movable along said table, a roller, an eccentric connection on said carriage, means for shifting said eccentric for moving said roller toward and away from said film, and mechanism for reciprocating said carriage along said table.

5. A machine of the class described, comprising a table, rollers mounted on said table, a belt passing around said rollers and across said table, a bath arranged to have said belt pass therethrough for forming an impression film on the face thereof adapted to re-

ceive a design, and a roller movable along said table to create pressure on said film.

6. A machine of the class described, comprising a table, rollers mounted on said table, a belt passing around said rollers and across said table, a bath arranged to have said belt pass therethrough for forming an impression film on the face thereof adapted to receive a design, a roller movable along said table to create pressure on said film, and means for shifting said bath into and out of position for coating said belt.

7. A machine of the class described, comprising a horizontally disposed table, rollers mounted at the ends of said table, another roller mounted below one of said first mentioned rollers, an idler mounted on said table inwardly and above said other roller, a belt passing over said rollers and idler and across said table, a trough embracing said other roller and adapted to contain a bath for coating said belt with an impression film adapted to receive a design, means for moving said belt through said bath and onto said

table, and a roller movable along said table for creating pressure on said film.

8. A machine of the class described, comprising a horizontally disposed table, rollers mounted at the ends of said table, another roller mounted below one of said first mentioned rollers, an idler mounted on said table inwardly and above said other roller, a belt passing over said rollers and idler and across said table, a trough embracing said other roller and adapted to contain a bath for coating said belt with an impression film adapted to receive a design, means for moving said belt through said bath and onto said table, a roller movable along said table for creating pressure on said film, a drum mounted on said table, flexible means connecting said trough to said drum so as to shift said trough into and out of position for immersing said belt in said bath.

Signed at Chicago this 28th day of August 1915.

PAUL G. SHOURDS.
